UNITED STATES PATENT OFFICE

DAVID T. WADSWORTH, OF COLD SPRINGS, KENTUCKY, ASSIGNOR TO THE WADSWORTH ELECTRIC MANUFACTURING COMPANY, OF COVINGTON, KENTUCKY, A CORPORATION OF KENTUCKY

LATCHING AND SEAL RECEIVING STRUCTURE

Application filed January 13, 1927. Serial No. 160,991.

This invention relates to a latching and seal receiving structure for use in securing cover members to cabinets and the like which are also to be sealed against unauthorized

Another object is to provide a latching and seal receiving structure which serves to relieve a seal of such strains and stresses as may be applied to the inner face of a cabinet cover.

Another object is to provide a switch box structure embodying the latching and seal receiving structure of my invention wherein the latching element co-operates with a switch operating interlock mechanism for providing a simple and efficient safety switch box.

These and other objects are attained by the means described herein and disclosed in the accompanying drawings, in which:

Fig. 1 is a perspective view of a safety box having embodied therein the latching and seal receiving element of the invention and showing also the interlock mechanism of the invention.

Fig. 2 is a cross sectional view taken on line 2—2 of Fig. 1.

Fig. 3 is a fragmental side elevational view of the device in latched position, parts being broken away.

The device of the invention is herein embodied in a switch box having side walls 5 and 6 and a hingedly mounted cover 7. The cover 7 is provided with side flanges 8 and 9 and top and bottom flanges 10 which receive between them the forward edges 11 of the side walls 5 and 6 and the top and bottom walls of the cabinet. The side flange 9 is hingedly mounted to the side wall 6 of the box or cabinet. Upper and lower hinges such as 12 (see Fig. 2) are employed and they comprise sheet metal members somewhat like cotter pins with a loop passing through the flange 9 and the lugs thereof

spread on the inside of the cabinet after passing through the wall 6. The opposed flange 8 has an integral lug 13 struck from the body thereof and the end portion of the lug 13 is disposed in parallel offset relation to the outer face of the flange 8 for providing a seat

14 into which latch member 15 may be received. The latch member 15 comprises a body portion pivotally mounted as at 16 to the side wall 5 of the cabinet and is offset as at 17 for a distance equal to the thickness of the flange 8. This relation of parts permits the latch member 15 to be moved downwardly about its pivotal mounting and to seat in the way 14 between the inner face of lug 13 and the outer face of flange 8. The latch member is provided intermediate its ends with a hook 18 having an arcuately disposed face 19 which rides over the forward edge 20 of that portion of lug 13 which extends outwardly from the flange 8. From the foregoing it will be apparent that as soon as any portion of the hook 18 of latch 15 passes over the forward edge 20 of lug 13, it will be impossible to open the cover 7. When the hook 18 is seated in the way 14, the edge 21 of latch 15 will rest in the bottom of the way 14 against the lower portion of lug 13 and face 19 of the hook portion 18 will be in abutment of the forward edge 20 of lug 13. At this time a seal receiving perforation 22 on the free end of latch 15 will coincide with perforation 23 of flange 24 which is secured to the cover 7 and has one face 25 in substantial alignment with the outer face of flange 8. The flange 24 may be formed of a right angle member rigidly secured to the front face of cover 7 by any suitable means such as spot welding, rivets or the like. From the foregoing it will be apparent that when the latch 15 is in the closed position, as shown in Fig. 3, a suitable seal 25 may have its strap or wire member passed through the perforations 22 and 23 in the latch and flange members so that it will be impossible to move the latch member 15 about its pivotal mounting sufficiently to remove the hook 19 from lug 14, without breaking the seal 25. It will also be apparent that any force tending to open the cover 7 will be directed against the rigid latch structure, so that there is no danger of exerting any shearing action on the wire or strap portion of the seal 25.

In the herein described switch box there is provided an interlock mechanism which pre-

cludes access to the interior of the fuse compartment 26 when the switch operating arm is in the "on" position. A switch crank comprising a handle lever 27 and a switch rod 28 is pivotally mounted in the side walls 5 and 6 as shown in Fig. 2. The switch rod 28 has an offset portion 29 which assumes a position adjacent the inner face of the cover 7 when the switch is moved to the "on" position through the agency of switch lever 27. When the lever 27 is moved to throw the switch to the "off" position, the offset portion 29 in the switch rod assumes a position further removed from the inner face of the cover 7. The cover 7 has a fuse opening 30 which is controlled by a shutter 31 slidably mounted on the interior face of the cover 7 by means of flanges 32. A rib 33 projects rearwardly of the shutter 31 and is secured thereto by means of a bracket 34 which overhangs one of the flanges 32 which retains the shutter in position. A knob 35 provides a convenient means for slidably actuating the shutter 31 and when said shutter is in the open position as shown in Fig. 1, the knob 35 moves into vertical slot 36 in the cover 7.

As will be readily noted in Fig. 1, the rib 33 assumes a position in the path of movement of the offset portion 29 of the switch rod when the shutter 31 is in its lowered or opened position. Assuming that the latch 15 is in closed position (as shown in Fig. 3) an attempt to move the arm 27 upwardly for closing the switch (not shown) will result in moving the offset portion 29 into abutment with the edge 37 of rib 33 thereby precluding closing of the switch. Force exerted upon the switch lever 27 will be directed, through offset 29 and rib 33 to door and is resisted by the hook portion of the latch member so that there is no possibility of even partial opening of the cover and therefore no strain can be exerted upon the seal 25.

When it is desired to close the switch, the shutter 31 must first be raised in order to remove the rib 33 from the path of the offset 29 in the switch rod. The lever 27 may then be raised for closing the switch and when in its fully closed position abuts the bottom edge 38 of the rib 33. From this it will be apparent that if an attempt is made to open the shutter 31 without first opening the switch, the end 38 of the rib 33 will automatically open the switch by forcing the offset portion 29 of the switch rod through its normal path in opening the switch. For this reason it is impossible to have access to the fuses while the switch is in the "on" position.

The latch structure not only serves to prevent accidental shearing of the seal, but also co-operates with the switch crank and fuse shutter in providing a simple and efficient safety interlock mechanism for switches.

What is claimed is:

1. A latch for securing an angularly flanged cover to a side wall received thereby comprising a latch body adapted for pivotal mounting on the exterior facing of the side wall and having an arcuate edged lug movable therewith substantially beyond the face of the cover, the cover flange having an outwardly struck lug providing an open topped way for entry of the latch member and the lug presenting an edge cooperating with the arcuate edge of the lug on the latch member. 70

2. A latch and seal receiving structure for a cabinet having a side wall and a movable angularly flanged cover, the flange embracing the side wall and having an outwardly struck transverse lug, said structure comprising a latch pivotally mounted on the side wall and movable for entry into the space between said lug and the cover flange and extending beyond the face of the cover, the free end of the latch being perforate, the cover having a member perforated to coincide with the perforation of the latch, and an arcuate edged hook disposed in a plane with the latch member and movable therewith for engagement of the arcuate edge with an edge on the flange lug. 80

3. In a latching and seal receiving structure for a cabinet having a side wall and cover adapted to abut the edge of the side wall, the cover having a flange provided with a lug, said structure comprising a member with a terminally offset portion for pivotal mounting on the side wall, said member having a laterally extending offset hook with an arcuate edge concentric with the pivotal mounting and co-operating with the lug on the flange to retain the cover in closed position during a predetermined pivotal movement of the member, said member having in its free end a perforation for cooperation with a suitable perforate member on the cover for receiving a seal whereby pivotal movement of the member is limited to preclude disengagement of the arcuate edge of the lug. 90

In testimony whereof, I have hereunto subscribed my name this 30th day of December, 1926.

DAVID T. WADSWORTH.
